ELECTRIC SWITCH.

1,412,570.

Specification of Letters Patent. Patented Apr. 11, 1922.

Application filed August 9, 1919. Serial No. 316,385.

To all whom it may concern:

Be it known that I, HERMAN G. PAPE, a citizen of the United States, residing in the borough of Manhattan, city, county, and 5 State of New York, have invented an Improvement in Electric Switches, of which the following is a specification.

This invention relates to an electric switch and as illustrated and described is applied 10 to a pull socket fixture, although as will be understood, the invention is not limited to this particular use. The switch made in accordance with the present invention embodies the use of the mechanical movement 15 shown and described in Letters Patent No. 1,190,451, dated July 11, 1916, and is, as applied to a socket fixture, an improvement on the structure shown and described in Letters Patent No. 1,216,483, although the 20 mechanical movement employed in the present invention is one which also includes a driving member for actuating a driven member carrying the switch contacts with a quick snap action, and also includes an 25 actuating device or auxiliary driving member, together with means for normally returning the auxiliary driving member in such a normal position as to successively 30 actuate the main driving member in preferably opposite directions so as to operate the driven member accordingly.

In carrying out the invention, there is employed a driven or switch contact carrying member adapted to bear against contact 5 terminals of the switch in one position and to be removed therefrom in the other position, a main driving member, a tension device for connecting the main driving member and the driven or switch contact carrying member, and auxiliary driving means 10 for actuating the main driving means together with devices for operating the auxiliary driving member and returning the same to a normal position so that successively the auxiliary driving member is operated in different directions. The invention also includes a novel means for connecting the pull chain or other device employed to the auxiliary driving member, and as employed in a socket, it includes a novel manner in connecting the socket terminals in the base thereof.

In the drawing: Figure 1 is a transverse cross section on line 1—1, Fig. 2.

Fig. 2 is a central longitudinal cross section on line 2—2, Fig. 1.

Fig. 3 is a view similar to Fig. 1, showing the parts in a different position.

Fig. 4 is a central longitudinal cross section and elevation showing the parts in the 60 position as shown in Fig. 3.

Fig. 5 is a plan of the actuating member.

Fig. 6 is a cross section on line 6—6, Fig. 5.

Fig. 7 is a plan of the auxiliary driving 65 member.

Fig. 8 is a cross section shown on line 8—8, Fig. 7.

Fig. 9 is a plan of the driven member carrying the switch contacts.

Fig. 10 is a cross section on line 10—10, Fig. 9.

Fig. 11 is a plan of the main driving member.

Fig. 12 is a cross section on line 12—12, Fig. 11.

Fig. 13 is a partial cross section illustrating the manner in which the pull chain is attached to the auxiliary driving member and maintained in position in the socket.

Fig. 14 is a partial plan of the parts shown in Fig. 13.

Fig. 15 is a plan view showing the operating parts of the mechanism in one position.

Fig. 16 is an edge elevation of the same.

Fig. 17 is a plan view of the operating parts of the switch mechanism showing the same in the other position.

Fig. 18 is a side or edge elevation of the parts in the position as shown in Fig. 17, and

Fig. 19 is a partial central cross section taken through the pin on which the parts of the switch mechanism are mounted.

Referring to the drawing, the electric 95 switch embodying the present invention as applied to a pull socket fixture preferably comprises a two part base block, the parts of which are suitably connected. One part of the base block is indicated at 10 and the 100 other part of the base block is indicated at 11. These base block members as will be understood may be made of porcelain or any other suitable insulating material. As illustrated, these base block members are connected in spaced positions by a bracket 12. One arm 13 of this bracket 12 is connected by screws or otherwise to the 105

base block member 11, and the other arm 14 of the bracket is connected to the base block member 10 in the same manner.

- In the arm 14 and preferably in the central portion thereof there is a pin or bolt 15 which extends outwardly therefrom toward the base block member 11. Mounted so as to turn freely on the bolt 15 there is a collar 16' with which the movable members of the switch are associated. One of these members is a driven member indicated at 16 and carries the movable contacts of the switch mechanism. This driven member 16 is provided centrally with an aperture 17 adapted to fit over and to be received upon the reduced inner end of the collar 16' as is clearly indicated in Fig. 19, and this driven member 16 is also provided with a recess 18 which is substantially concentric with the aperture 17.
- 20 The driven member 16 also includes an angular portion 19 adapted to extend into the recessed part 20 of the base block member 10, and at the extremity of the angular extension a plate 21 of suitable insulating material is secured by means of rivets 22 or otherwise. The outer edge of the plate of insulating material is preferably made on the arc of a circle and is provided with spring contacts 23 and 24. As illustrated, these 25 spring contacts are formed of loops of conducting material which at the turned portion is fitted into slots 25 and 26 extending radially into the plate of insulating material with a portion of each strip extending along the opposite surfaces of the plate of insulating material and then turned outwardly to form the movable contacts of the switch. The driven member 16 is also provided with a lug 27 in which the corresponding ends of 30 springs 28 and 29 are connected, these springs being a continuous piece of resilient wire as illustrated in Fig. 9, if found desirable. Furthermore, the driven member 16 includes a projection 30, which, as herein- 35 after described, is adapted to contact with the stops 31 and 32 connected to or forming part of the transverse portions of the bracket 12 to limit and determine the extent of the movement of the driven member 16 and the 40 movable contact carried thereby. Also in the driven member 16 there is a small hole 33, the purpose of which will be hereinafter indicated.
- 45 Together with the driven member and the parts associated therewith as hereinbefore described, I employ a main driving member 34 which is illustrated in detail in Figs. 11 and 12. The main driving member 34 is preferably made of thin metal and centrally 50 provided with an aperture 35 adapted to fit over the reduced outer end of the collar 16', and the main driving member is preferably connected securely to this collar 16' in any suitable manner so as to turn therewith.
- 55 In suitable positions this main driving mem-

ber 34 is provided with arms 36 and 37, in the edges of which there are respectively the recesses 38 and 39. The main driving member 34 is also provided with an angular extension 40, the extremity of which lies parallel to and spaced from the body of the main driving member and is provided with a small hole 41. Associated with and connecting the driven member and the main driving member 34, I employ a spring 42, preferably having a loop coil 43. One end of the spring 42 is fixed in the small hole 33 in the driven member 16 and the opposite end of the spring 42 is fixed in the small hole 41 in the main driving member 34 so that the spring is made to oscillate on an axis which is perpendicular to the movement of the driven member 16 and the main driving member 34, the action being such that when the main driving member 34 is oscillated through a predetermined portion of a revolution in one direction, sufficient tension is applied to the spring 42 to cause a quick snap oscillating movement of the driven member through a corresponding portion of a revolution, the movements being such that when the main driving member is oscillated clock-wise, the driven member carrying the movable switch contacts is oscillated counter clock-wise and vice versa.

55 In the structure as shown and described, I also employ an auxiliary driving member 44 illustrated in detail in Figs. 7 and 8. This auxiliary driving member 44 is also made of thin metal and is provided adjacent one end 100 with an aperture 45 of substantially the same diameter as the aperture 35 in the main driving member 34 so as to be received on the reduced outer end of the collar 16' and to lie against the outer face of the main driving member and to turn freely on the collar. At the end opposite that in which it is pivotally connected, the auxiliary driving member is provided with a bracket 46 which is notched as indicated at 47 to receive the end 105 of a pull chain or cord 48 by which, as hereinafter described, the movable parts of the switch are operated by pulling and releasing the chain or cord. This auxiliary driving member is also provided with a tongue 49 110 extending from the reverse face thereof and provided with slots 50 and 51 as well as a notch 51'. The slot 51 is adapted to receive the free end of the spring 28 and the slot 50 to receive the free end of the spring 29, in 115 order that through the action of these springs, the auxiliary driving member is returned and normally maintained in its operative position.

120 The movable parts of the switch mechanism also include an actuating member 52 which is shown in detail in Figs. 5 and 6. This actuating member is also preferably made of thin metal and is provided in the required position with an aperture 53 of the 125

same diameter as the apertures in the main and auxiliary driving members so as to also be received on the reduced outer end of the collar 16' with the inner face of the actuating member lying against the outer face of the auxiliary driving member so that the actuating member is also free to turn on the collar. Furthermore, as indicated in Fig. 19, the outer reduced end of the collar 16' 5 may be upset against the outer surface of the actuating member 52 so as to maintain the same and the auxiliary driving member 44 in position on the collar. The actuating member 52 also includes shoulders 54 and 55 in 10 oppositely disposed positions as well as a shoulder 56 at the end of the member opposite the shoulders 54 and 55. When the operating parts of the switch, as hereinbefore described, are in their assembled positions, 15 the driven member is appreciably spaced from the main driving member by a portion of the sleeve 35 which acts as a spacer and the reverse side of the auxiliary driving member lies against the obverse face of the 20 main driving member with the tongue 49, the auxiliary driving member extending over the main driving member, a portion of the periphery of the latter lying within the notch 51' of the former so as to maintain the parts 25 in their associated relationship. The reverse side of the actuating member 52 also preferably lies against the obverse face of the auxiliary driving member with the shoulders 54 and 55 spanning the auxiliary driving member 30 and lying against the obverse face of the main driving member, while the shoulder 56 extends beyond the edge of the main driving member and its opposite ends, that is the opposite ends of the shoulder 56 are adapted to 35 engage alternately in the notches or recesses 40 and 39.

Suitably fixed in the base block member 10, 45 there is a stationary contact 57. This is preferably secured in position by a screw or bolt 58 passing through the reduced section of this base block member and connected electrically with a screw socket 59. Also connected to the base block member 10 within the screw socket 59 and at the base thereof 50 as is customary, I employ a central contact member 60. This central contact member 60 is electrically connected to a stationary contact 61 which also passes through the reduced part of the base block member 10 and 55 is secured therein by a screw or bolt 62, the contact 57 and the contact 61 being adapted to be engaged by the movable contacts 24 and 23 respectively.

In the base block member 10, there is also 60 secured a terminal 63 fitted with a screw binding post 64 and the terminal 63 is electrically connected to a stationary contact 65 by means of a contact bar 66 or otherwise. The stationary contact 65 is disposed oppositely to the stationary contact 57 so that in

one position the movable contact 24 simultaneously engages both the stationary contacts 57 and 65. Also mounted in a recess provided therefor in the periphery of the base block member 10 is a terminal 67. This terminal 67 is fitted with a screw binder post 68 and is electrically connected to a stationary contact 70 by means of a contact bar 69 or otherwise. The stationary contact 70 is oppositely disposed to the stationary contact 61 70 so that in one position the movable contact 23 is adapted to simultaneously engage both the stationary contact 61 and the stationary contact 70. The longitudinal recess in which the terminal 63 is mounted is indicated at 75 71, and the longitudinal recess in which the terminal 67 is mounted is indicated at 72, and as will be understood, these recesses are sufficiently deep to receive the terminals and their screw binding posts so as to connect the 80 lead wires thereto and set the binding post in position without interfering with the shell or cover which may be employed with the switch when used in a socket or other apparatus.

Also as illustrated in the drawing, the switch mechanism as employed in a socket may be fitted with a shell or cover 73 which is provided with a chain guide or conduit 74 through which the pull chain 48 passes and 85 is available for use.

Assuming the parts of the switch mechanism as hereinbefore described to be in the position shown in Figs. 1 and 2, it will be observed that the contact carrying member, 100 that is to say, the driven member 16 is in the position with the movable contacts 24 and 23 therein respectively against the stationary contacts 57 and 65 and 61 and 70. In this position the projection 30 bears 105 against the stop 32 carried by the right hand post of the bracket as viewed in Fig. 1. It will also be observed that the main driving member is in that position in which the arm 37 bears against the same post 12, 110 and that the outer end of the auxiliary driving member lies at the left of the central axis as shown in this figure and contacts with the shoulder 54 of the actuating member 52. Now by pulling on the chain 115 48, the auxiliary driving member is caused to oscillate in a counter clock-wise direction carrying with it the actuating member 52. The continued movement of these members by pulling on the chain brings 120 the end of the shoulder 56 into engagement with the notch 39 in the main driving member so that by the further movement of the auxiliary driving member and the actuating member, the main driving member 125 is caused to oscillate in a counter clock-wise direction against the action of the spring 29, and when this movement has been continued sufficiently far, the tension applied to the spring 42 is increased until 130

it becomes sufficient to actuate the driven member and the contacts carried thereby in a clock-wise direction and with a quick snap action so as to remove the movable contacts from the fixed contact. When this movement has been completed and the chain released, the spring 29 returns the auxiliary driving member and the actuating member to a position on the other side of the central axis as shown in Fig. 1 so that the parts are adapted, by pulling on the chain, to be moved in the opposite direction to cause the driven member with the contacts carried thereby to be moved again with a quick snap action into contact with the stationary contacts, or in other words, to be returned to a position of the parts as shown in Fig. 1, it being understood that the stops 31 and 32 limit the respective movements of the driven member by the projection 30 coming in contact therewith, while the posts forming part of the bracket limit the movement of the main driving member by the arms 36 and 37 coming into contact therewith, and also that the return movement of the auxiliary driving member to the position shown in Fig. 1 is caused by the action of the spring 28.

By reference to Figs. 13 and 14, it will be seen that the upper or outer block 11 of the base block is provided with a recess 75 which is so placed as to lie centrally over the outer end of the auxiliary driving member 44, that is, when the auxiliary driving member is in its central position, the notch 47 therein lies immediately under this recess and as the auxiliary driving member is never normally stopped in this position, that is normally it is always at one side or the other of this central position, and as the bracket 46 lies in close proximity to the under surface of the base block member 11, the pull chain member 48 may be placed in position in the notch 47 by holding the auxiliary driving member in its central position, and in the same position it may be as readily moved from the notch. In view of this structure as will be apparent, the base block member 11 coacts with the bracket 46 to maintain the pull chain in position in the notch in the bracket.

I claim as my invention:

1. An electric switch comprising an oscillating contact member, a main driving member, an auxiliary driving member, means for connecting the oscillating contact member and the main driving member, whereby when the main driving member is turned in one direction the contact member is turned in the opposite direction, and devices for actuating the auxiliary driving member to turn the main driving member first in one direction and then in the other.

2. An electric switch comprising an oscillating contact member, a main driving mem-

ber, an auxiliary driving member, a spring connecting the oscillating contact member and the main driving member and adapted to oscillate on an axis perpendicular to planes in which the said contact member and main driving member turn, and devices for actuating the auxiliary driving member to turn the main driving member first in one direction and then in the other. 70

3. An electric switch comprising an oscillating contact carrying member, a main driving member adapted to oscillate in a plane parallel to the plane in which the contact carrying member oscillates, a tension device for connecting the said contact carrying member and the main driving member, an auxiliary driving member adapted to oscillate in a plane parallel to the planes in which the main driving member and contact carrying member oscillate, and an actuating member 80 for moving the auxiliary driving member, with the said contact carrying member, main driving member, auxiliary driving member and actuating member all oscillating about a common axis. 85

4. An electric switch comprising an oscillating contact carrying member, a main driving member adapted to oscillate in a plane parallel to the plane in which the contact carrying member oscillates, a spring 95 connecting the oscillating contact member and the main driving member and adapted to oscillate on an axis perpendicular to planes in which the said contact member and main driving member turn, an auxiliary driving member adapted to oscillate in a plane parallel to the planes in which the main driving member and contact carrying member oscillate, an actuating member for moving the auxiliary driving member, with the said contact carrying member, main driving member, auxiliary driving member and actuating member all oscillating about a common axis, and means for operating the actuating member. 100

5. An electric switch comprising an oscillating driven member, a contact carried thereby, an oscillating main driving member, an oscillating auxiliary driving member cooperating with the main driving member, an actuating member cooperating with the auxiliary driving member, all of said members being mounted to oscillate about a common axis, means connecting the driven member and the main driving member to cause the driven member to be actuated by the main driving member, and a resilient member carried by the driven member and cooperating with the auxiliary driving member to return and maintain the same in a normal position for operating the main driving member. 115

6. An electric switch comprising an oscillating driven member, a contact carried thereby, an oscillating main driving mem- 120

ber, an auxiliary driving member cooperating with the said main driving member, all of the said members being mounted to oscillate about a common axis, a spring connecting the driven member and the main driving member to hold the same in a fixed position and to cause the driven member to be actuated by the main driving member, a resilient member carried by the driven member and cooperating with the auxiliary driving member to return and maintain the same in a normal position for operating the main driving member, and a stationary contact against which in one position the aforesaid contact is adapted to bear.

7. An electric switch comprising an oscillating driven member, a contact carried thereby, an oscillating main driving member, an oscillating auxiliary driving member, all of said members being mounted to oscillate about a common axis, a spring for connecting the driven member and the main driving member, which spring oscillates on an axis perpendicular to the direction of the movements of the said members, a second spring carried by the said driven member and cooperating with the said auxiliary driving member to normally maintain the same in a position for operating the said driving member, and a stationary contact against which when in one position the aforesaid contact is adapted to bear.

8. An electric switch comprising an oscillating driven member, a contact carried thereby, an oscillating main driving member, an auxiliary driving member, all of said members being mounted to oscillate about a common axis, a spring connecting the driven member with the main driving member so that when the main driving member is oscillated in one direction by the auxiliary driving member, the driven member will be oscillated in the opposite direction by said spring, a second spring carried by the driven member and cooperating with the auxiliary driving member to return and normally maintain the said auxiliary driving member in position to actuate the said main driving member, and a stationary contact against which when in one position the aforesaid contact is adapted to bear.

9. An electric switch comprising a driven member, a contact carried thereby, a main driving member, an auxiliary driving member, an actuating member, tension means connecting the driven member and the main driving member, a resilient member connected to and carried by the driven member and cooperating with the auxiliary driving member to return the same and the actuating member to normal positions for operating the said main driving member, and a stationary contact against which when in one position, the aforesaid contact is adapted to bear.

10. An electric switch comprising an oscillating driven member, a contact carried thereby, an oscillating main driving member, an oscillating auxiliary driving member, an oscillating actuating member, all the said members being mounted to oscillate about a common axis, a tension device for connecting the driven member and the main driving member so that the driven member is caused to oscillate with a quick snap action by the movement of the main driving member, a resilient member connected to and carried by the driven member and cooperating with the main driving member for returning and normally maintaining the same and the actuating member in position for operating the main driving member, and a stationary contact against which when in one position the aforesaid contact is adapted to bear.

11. An electric switch comprising an oscillating driven member, a contact carried thereby, an oscillating main driving member, an oscillating auxiliary driving member, an oscillating actuating member, all of said members being pivotally mounted to oscillate about a common axis with the driving member actuated by the auxiliary driving member through the said actuating member, a spring connected at one end to the said driven member and at the other end to the main driving member so that when the main driving member is oscillated in one direction, the said spring causes the driven member to be oscillated in the opposite direction with a quick snap action, a second spring connected to and carried by the driven member and cooperating with the auxiliary driving member for returning and normally maintaining the same and the actuating member in position to operate the main driving member in one of two directions, and a stationary contact against which when in one position the aforesaid contact is adapted to bear.

12. In an electric switch, a stationary contact, a movable contact, means for carrying the movable contact, an actuating member for driving the aforesaid means, devices for normally maintaining the actuating member on either one side or the other of a center line, a pull chain for operating the actuating member, and means whereby the pull chain may be connected to the operating member and disconnected therefrom only when the operating member is in a centrally disposed position.

13. In a pull socket electric switch, a base block, fixed contacts thereon, movable contacts, a member for carrying the movable contacts, a driven member for actuating the member carrying the movable contacts, means for normally maintaining the driven member on either one side or the other of a center line of the base, a pull chain, and

means whereby the pull chain may be connected and disconnected to the drive member only when the drive member is in a centrally disposed position.

- 5 14. In a pull socket electric switch, a base block, fixed contacts thereon, movable contacts, a member for carrying the movable contacts, a driven member for actuating the member carrying the movable contacts,
10 means for normally maintaining the driven member on either one side or the other of a center line of the base, a pull chain, and

means for connecting and disconnecting the pull chain to the drive member only when the drive member is in a central position, the 15 said drive member being so disposed in relationship to a part of the base block that the drive member and base block coact to maintain the pull chain in connection with the drive member in all positions except 20 a central one.

Signed by me this 8th day of August, 1919.

HERMAN G. PAPE.
